DESIGN FOR A BONNET OR SIMILAR ARTICLE

Evelyn Hornsby Mims, Fort Worth, Tex.

Application June 13, 1935, Serial No. 57,250

Term of patent 14 years

To all whom it may concern:

Be it known that I, Evelyn Hornsby Mims, a citizen of the United States residing at Fort Worth, in the county of Tarrant and State of Texas, have invented a new, original, and ornamental Design for a Bonnet or Similar Article, of which the following is a specification, reference being had to the accompanying drawing, forming part thereof.

Fig. 1 is a side elevation of a bonnet showing the new design.

Fig. 2 is a perspective view of the same, taken from the rear.

Fig. 3 is a similar view, taken from the front thereof.

I claim:

The ornamental design for a bonnet or similar article, as shown.

EVELYN HORNSBY MIMS.
